UNITED STATES PATENT OFFICE.

ADALBERT KOHN, OF PILSEN, AUSTRIA-HUNGARY.

LUBRICATING DEVICE FOR SLIDE-VALVES.

SPECIFICATION forming part of Letters Patent No. 745,630, dated December 1, 1903.

Application filed January 19, 1903. Serial No. 139,520. (No model.)

To all whom it may concern:

Be it known that I, ADALBERT KOHN, works foreman, a subject of the Emperor of Austria-Hungary, residing at Pilsen, Bohemia, Austria-Hungary, have invented certain new and useful Improvements in Lubricating Devices for Slide-Valves, of which the following is a full, clear, and exact description.

The present invention relates to means for lubricating the faces of slide-valves, and its particular object is to apply the lubricating medium directly to the face of the valve. In order to attain this object, the oil is fed to the valve-face through the steam-ports by a series of injector-jets, so that the lubricating medium will be sprayed onto the face of the valve in spite of the steam-pressure existing in the ports.

In order to render the present specification easily intelligible, reference is had to the accompanying drawings, in which similar letters of reference denote similar parts throughout the several views.

Figure 1 is a cross-section through a steam-cylinder and steam-chest, showing the arrangement of the lubricating-nozzles. Fig. 2 is a horizontal section through the steam-chest, and Fig. 3 is a detail view showing the arrangement of a nozzle for inclined valve-faces.

According to the device illustrated in Figs. 1 and 2 the pipe *b* leads from the lubricator and passing through the side walls of a steam-port ends in a nozzle *a*, which may be provided with two or more openings or jets. Each nozzle is located in a steam-port, and the oil will be directed by the same onto the face of the slide-valve, as will be readily understood.

In addition to the thorough lubrication of

the valve-faces attained by this method of lubricating the steam entering the cylinders will also be lubricated and will properly lubricate the piston of the cylinder.

For inclined valve-faces the arrangement 45 of a single opening in the nozzle, as at *a* in Fig. 3, will be sufficient, since the oil will run down the inclined surface. In the arrangement shown in Fig. 1 the nozzle is advantageously provided with two or more openings, 50 so that the oil will be distributed over the whole valve-face evenly.

I claim as my invention—

1. In combination with a steam-cylinder, valve and steam-port, of means for spraying 55 the lubricating medium within the steam-port directly onto the face of the valve, substantially as described.

2. In combination with a steam-cylinder, valve and steam-port, of means within the 60 port for spraying the lubricating medium directly onto the face of the valve, substantially as described.

3. In combination with a steam-cylinder, valve and steam-port, of a nozzle located with- 65 in the port for spraying the lubricating medium directly onto the face of the valve, substantially as described.

4. In combination with a steam-cylinder, valve and steam-port, of a nozzle located with- 70 in the port for spraying the lubricating medium directly onto the face of the valve, the said nozzle having a plurality of openings or jets, substantially as described.

In witness whereof I have hereunto set my 75 hand in presence of two witnesses.

ADALBERT KOHN.
